UNITED STATES PATENT OFFICE.

FRIEDRICH SOHMEMANN, OF PHILADELPHIA, PENNSYLVANIA.

ELEVATED RAILROAD AND BRIDGE.

SPECIFICATION forming part of Letters Patent No. 314,728, dated March 31, 1885.

Application filed February 28, 1884. (No model.)

To all whom it may concern:

Be it known that I, FRIEDRICH SOHMEMANN, a citizen of the United States, residing in the city and county of Philadelphia, State of Pennsylvania, have invented a new and useful Improvement in Bridges, Elevated Roads, &c., which improvement is fully set forth in the following specification and accompanying drawings, in which—

- 10 Figure 1 is a side elevation of a bridge embodying my invention. Fig. 2 is a transverse section thereof. Fig. 3 is a side elevation, partly sectional, of the lower portion of one of the columns. Fig. 4 is a vertical section 5 of Fig. 3. Fig. 5 is a side elevation, partly sectional, of the upper portion of the column. Fig. 6 is a vertical section thereof. Fig. 7 is 15 a side elevation, enlarged, of portion of the reversed arches of the bridge, including portions of the ties thereof in vertical section. Fig. 8 is a transverse vertical section of Fig. 7. Fig. 9 is a top view of one of the couplings 20 of the arches. Fig. 10 is a longitudinal vertical section thereof. Fig. 11 is a partial side 25 elevation and partial vertical section of portion of an auxiliary arch of the bridge. Fig. 12 is a transverse vertical section thereof. Fig. 13 is a side elevation, partly sectional, of the roadway and crown of the auxiliary arch. Fig. 14 30 is a transverse vertical section of Fig. 13. Fig. 15 is an enlarged view, partly sectional, of a portion of Fig. 2.

Similar letters of reference indicate corresponding parts in the several figures.

- 35 My invention consists of a bridge provided with a longitudinal series of reversed arches intersecting each other between their ends and united at their points of intersection.

It further consists in a bridge having reversed arches extending in the transverse direction thereof.

It further consists in a bridge having reversed arches extending in the longitudinal and transverse directions thereof.

- 45 It further consists in a bridge having reversed arches and auxiliary arches, both extending in the longitudinal direction thereof, arranged in series and secured together.

It further consists in a bridge provided with 50 a series of connected reversed arches and locks for the same, which consist of devices which

extend across the space between each upper and lower arch, and are secured to them.

It further consists in a column consisting of inner pipes and an outer pipe, the latter being 55 screw-threaded for the attachment of laterally-extending parts.

It further consists in a column provided with a saddle having a convex top, in combination with a bent sleeve fitting on said saddle, a cap which holds said sleeve down on the latter, and a lower chord, the sections of which are screwed into the ends of said tube. 60

It further consists in a tubular column the lower section of which is in combination with 65 a sleeve which is screwed directly upon it, and provided with external tenons for receiving the ends of the tubular chords.

It further consists in a bridge having longitudinal and cross chords or arches in reversed 70 order, and connecting-couplings, combined and operating substantially as hereinafter set forth and claimed.

It further consists in a bridge having two intersecting chords or arches, in combination 75 with a coupling attached thereto at their intersection, said coupling being provided with external tenons for attaching one chord or arch, a screw-threaded inner portion for attaching the other chord or arch, and tenons 80 which extend inwardly from said outer portion of the coupling nearly to said inner portion thereof, and serve as braces.

It further consists in an arch-truss consisting of horizontal upper chords formed of tubes 85 attached to a coupling by screw-threads, and a lower chord forming an arch, both connected by means of vertical columns and screw-threaded hollow tenons, all substantially as hereinafter set forth and claimed. 90

Referring to the drawings, A represents the columns of the bridge, the same consisting of a series of tubes inclosed one within the other, resting on a common base, a. The outer tube terminates at top below the road-bed of the 95 bridge, and is screw-threaded for the connection of a sleeve, B, from which project in longitudinal and transverse directions three tenons, B' B'', the tenons B' having fitted to them the ends of the compression or upper chord, C. 100

Resting on the top of the inner tubes of a column is a saddle, D, on which is supported

a sleeve, D', to which are screwed the ends of the tension or lower chord, E, of adjacent spans of the bridge, it now being seen that the two chords C E form reversed arches extending in the longitudinal direction of the bridge from column to column thereof. The chords or arches C E intersect each other between their ends, and are united at their points of intersection, by which means great strength is added to the structure.

Surmounting the saddle D is a cap, D'', which is fitted to an upwardly-projecting tubular extension of said saddle, the sleeve D' passing through an opening in said extension 15 while resting on the saddle.

Fitted to a tenon, B'', and resting thereon, is the transverse upper chord, F, and screwed to a boss, D''', which projects downwardly from the extended portion of the saddle, is the 20 transverse lower chord, G, it being noticed that the two chords F' G form reversed arches extending in the transverse direction of the bridge from each pair of columns. The reversed arches at their intersections, pass each 25 other by means of couplings H, to whose ends the arches are connected, the compression-chord being fitted to tenons on the outer portions of the couplings, and the tension-chords being screwed to the inner portions of said 30 couplings, (see Figs. 9 and 10,) the outer portion of the couplings having within it bosses b, which extend inwardly nearly to the inner portion of the coupling, and acting as braces therefor when under strain, thus vastly increasing 35 the strength of the coupling and the ability to endure the compression to which it may be subjected.

The roadway proper is constructed of a series of four longitudinal single arches, upon 40 which rest the horizontal upper chords, which latter carry the rails or roadway.

The construction is as follows: Running from one transverse reversed arch F G to another is a series of arches, K L M, the successive divisions of which are united by couplings N, to the bosses of which the lengths 45 constituting the arches are screwed.

Rising from the couplings N are bosses which receive loosely upright tubes carrying 50 on their upper ends T's or crosses P, to which the uprights are screwed. These crosses P have arms or bosses extending either way in longitudinal direction of the bridge, and receive, by means of a screw-thread, the tubes Q, 55 which form the horizontal upper chord. The crosses P also have bosses extending in transverse direction to receive tubes for lateral bracing. The couplings N also have laterally-extending bosses to receive tubes to brace the 60 arches K L M laterally. If desired and found essential, the sets of arches carrying a line of roadway may be laterally braced, similar to the bracing employed for the arch itself.

Mounted on the crosses P, or made integral 65 therewith, are castings, which have a recess, e, formed therein to receive a rubber or similar cushion, R, on which the rails are placed,

the latter being secured in position by means of clamps, which are bolted to the horizontal upper chord or to the crosses and against the 70 flange of the rail. It is evident that at the abutments proper anchorage must be provided to sustain the tension of the reversed arch or chord E, as well as proper trussing to brace the column against the action of the chord or arch C. The caps D'' may be closed at top, or may be arranged to receive lamps, statuary, or other articles of use or ornamentation, as is evident. 75

Referring to Figs. 7 and 8, the crowns of the main and cross arches or chords are respectively connected by means of sleeves C', fitted over the tubes of the main trusses, and secured by a set of rings, C'', the cross arches or chords being attached to said sleeves by screw-threads, as at d, and may be connected by cross-braces, 80 85 if desired. It will be seen that the reversed arches reduce the length of the span on which the load is acting a distance equal to the length from the crossing to crossing-point of the arches, from which points suspension and trussing are performed. The longitudinal intermediate single-arch trusses reduce the load on the main-arch trusses in the present case six-tenths, the other four-tenths going directly to the cross-arches of the main posts, reducing 90 95 considerably the weight of the intermediate structure. There is a continuous structure which has the advantage of a common truss in making the main posts or columns stiff, and as the spans form a continuous structure the latter is self-regulating in regard to expansion and contraction by changes of temperature for the inverted arches. In this respect the longitudinal single-track arches are provided for by means of the lock arrangement in the centers of the trusses. 100 105

The various tubes or pipes employed for the chords, &c., are formed of wrought-iron or steel, and the connections or couplings of cast-steel. The hollow round shape of the details 110 of construction is employed, owing to being perfect for compression and tension, first, on account of the shape of the section in regard to the moment of resistance, and, next, because there is no cramping of the material influenced 115 by the change of temperature. There is also presented the least possible surface for wind-pressure. It will also be seen that rivets, flanges, and bolts are dispensed with, thus vastly reducing the weight of the structure, 120 and there is generally a reduction both in weight and expense of the bridge, besides which the bridge has a light and graceful appearance, it being evident that the structure is serviceable for elevated railroads. 125 130

I am aware that it is not new to construct a bridge with raised arches on one side and reversed arches on the other, these arches being connected by bars or locking-pieces to a horizontal base.

I am also aware that it is not new to construct a bridge with two parallel reversed arches and an intermediate raised arch, each of these arches extending from end to end of

the bridge, and the reversed arches being connected to the raised arch or arches by interposed braces.

I am also aware that it is not new to make a bridge with two parallel raised arches and one reversed arch, the lines of the reversed arch and the upper raised arch intersecting, and these arches being connected together by interposed pieces both between their points of intersection and beyond the latter. I therefore do not claim any of these constructions and combinations of arches and interposed pieces; but,

Having thus described my invention, what I claim as new, and desire to secure by Letters Patent, is—

1. A bridge provided with a longitudinal series of reversed arches, C E, intersecting each other between their ends and united at their points of intersection, substantially as set forth.

2. A bridge having reversed arches extending in the transverse direction thereof, substantially as and for the purpose set forth.

25 3. A bridge having reversed arches extending in the longitudinal and transverse directions thereof, substantially as and for the purpose set forth.

4. A bridge having reversed arches and auxiliary arches, both extending in the longitudinal direction thereof, arranged in series and secured together, substantially as and for the purpose set forth.

5. A bridge provided with a series of connected reversed arches and locks for the same, which consist of devices which extend across the space between each upper and lower arch, and are secured to them, substantially as set forth.

40 6. A column consisting of the inner pipes and the outer pipe, A, the latter being screw-

threaded for the attachment of laterally-extending parts, substantially as set forth.

7. A column provided with a saddle, D, having a convex top, in combination with a bent sleeve, D', fitting on said saddle, a cap, D", which holds said sleeve down on the latter, and the lower chord, E, the sections of which are screwed into the ends of said tube, substantially as set forth.

50 8. The lower section of a tubular column, in combination with a sleeve, B, which is screwed directly upon it, and provided with external tenons, B', for receiving the ends of the tubular chords C, substantially as set forth.

55 9. The longitudinal and cross chords or arches in reversed order, as shown, and connecting-couplings, combined and operating substantially as and for the purpose set forth.

10. In a bridge, the combination of two intersecting chords or arches with a coupling attached thereto at their intersection, said coupling being provided with external tenons for attaching one chord or arch, a screw-threaded inner portion for attaching the other 60 chord or arch, and tenons b, which extend inwardly from said outer portion of the coupling nearly to said inner portion thereof, and serve as braces, substantially as and for the purpose set forth.

70 11. An arch-truss consisting of horizontal upper chords formed of tubes attached to a coupling by screw-threads, and a lower chord forming an arch, both connected by means of vertical columns and screw-threaded hollow 75 tenons, substantially as and for the purpose set forth.

FR. SOHMEMANN.

Corrections in Letters Patent No. 314,728.

It is hereby certified that in Letters Patent No. 314,728, granted March 31, 1885, for an improvement in "Elevated Railroads and Bridges," the name of the patentee was erroneously written and printed "Friedrich Sohmemann," whereas it should have been *Friedrich Schmemann*; that the proper corrections have been made in the file and records pertaining to the case in the Patent Office, and should be read in the Letters Patent to make the same conform thereto.

Signed, countersigned, and sealed this 16th day of June, A. D. 1885.
